UNITED STATES PATENT OFFICE.

GUNNAR CHRISTIAN EKSTRÖM AND GUSTAF ÖRSTRÖM, OF STOCKHOLM, SWEDEN, AS-
SIGNORS TO AKTIEBOLAGET GEHE. AREHNS MEKANISKA VERKSTAD, OF STOCK-
HOLM, SWEDEN, A CORPORATION OF SWEDEN.

PACKETING DEVICE FOR BOXES AND THE LIKE.

Application filed July 13, 1920. Serial No. 396,013.

To all whom it may concern:

Be it known that we, GUNNAR CHRISTIAN EKSTRÖM and GUSTAF ÖRSTRÖM, subjects of the King of Sweden, residing at Eriksbergs-
gatan 14 and Pålsundsgatan 6, respectively, Stockholm, in the Kingdom of Sweden, have invented certain new and useful Improvements in Packeting Devices for Boxes and the like, of which the following is a specification.

This invention relates to means for transporting to a packeting table, boxes or the like containing cigarettes or other articles and delivered, for instance, by a box filling machine. The said transporting device is so arranged that it delivers the boxes or packets on the table in a row of packets comprising sets of superposed packets, for instance five packets in each vertical set, the packeting of for instance, fifty packets, being thereby considerably facilitated. The packeting table may be common to two or more machines in which case, the transporting devices place the packets delivered by the machines respectively in corresponding rows on the table.

In the accompanying drawings a transporting device arranged in accordance with this invention is shown in a side view Fig. 1 and in a plan view Fig. 2. Figs. 3, 4 and 5 show details viewed from two different sides and from the top respectively. Fig. 6 is a fragmentary perspective view of one of the conveying channels removed.

In Figs. 1 and 2 three machines 1, 2 and 3 are shown, in which boxes, paper-bags or the like are filled with cigarettes or similar articles. The said machines may be of any known or suitable construction and, it may be, so arranged that they manufacture the boxes as well as fill the same with cigarettes. The machines are not described as they form no part of this invention. The boxes filled with cigarettes are delivered by the said machines 1, 2 and 3 into channels 4, 5 and 6 respectively, in which they are forwarded in the directions indicated by the arrows by reciprocating plungers, not shown, or in any other suitable manner. The said channels 4, 5 and 6 communicate with channels 7, 8 and 9 respectively extending substantially transversely to the channels 4, 5 and 6 and communicating with channels 10, 11

and 12 respectively, provided on a packeting table 13. According to the drawings the channels 10, 11 and 12 form right angles with the channels 7, 8 and 9. At the corners of the channels 4 and 7, 5 and 8, 6 and 9 transmitting means are provided, for moving the boxes from the channels 4, 5 and 6 into the channels 7, 8 and 9 respectively and forwarding the boxes in the channels last mentioned. The transmitting means at the said corners are of the same construction, for which reason only one of the same, provided at the corner of the channels 4 and 7, is described. Details of the said means are shown in Figs. 3, 4 and 5.

The width of the channel 7 is so adapted, that the channels may contain for instance five boxes *a* abreast. At the end of the channel 4 a feeler 14 is located, which is swingably mounted at 15 and acted upon by a spring 16 inward toward the channel 4. Normally the feeler 14 extends into the channel 4 acted upon by the spring 16 the position of the feeler being determined by an abutment. As the row of boxes *a* located in the channel 4 is advanced and the channel 4 is nearly filled with boxes, the feeler 14 is acted upon by the foremost box of the row and is swung outward into the position shown in the drawings. Feeler 14 has a projection 17, normally located in the path of a rod 18, which is movable in guides 19, forward and backward in the direction of the channel 7, and connected with a lever arm 20, swingably mounted at 21. To the rod 18 a plunger 22 is fixed, consisting in the drawings of a strip of sheet metal, bent as shown in Fig. 5. The plunger 22 is on a line with the channel 7 and the width of the front end 23 of the plunger corresponds to the number of boxes, five in the present case, to be transmitted from the channel 4 into the channel 7. A roller 24 on the lever arm 20 is forced by a spring 25 against a continuously rotating cam disk 26, which permits the spring 25 to move the plunger 22 inward towards the channel 7. Normally, the projection 17 of feeler 14 forms an abutment for the rod 18 and prevents such movement, but, as soon as the channel 4 is filled with boxes, the feeler 14 is forced outward by the row of boxes contained in the channel 4, as stated above, and its pro-

jection 17 moved out of the path of the rod 18, see Figs. 3 and 5. The plunger 22 then moves five boxes from the channel 4 into the channel 7 and, it may be, also forwards 5 in the channel 7 boxes previously pushed into the same. Plunger 22 moves the boxes for a distance somewhat greater than the length of the boxes.

All channels 7, 8 and 9 are constructed in 10 the same manner. The first part of each channel is trunk shaped and helicoidal an angle of 90° so that the bottom and the top walls of the channel will constitute the side walls of the same and one of the side walls 15 will form the bottom wall, as shown in Fig. 6. Owing to this arrangement, the boxes *a* of each set instead of being located side by side in a horizontal row as shown in the part of the Fig. 6, will be located one upon 20 the other in a vertical stack, as shown at the right hand end of Fig. 6. The sets of boxes located in the manner last mentioned are transmitted from the channels 7, 8 and 25 9 into the channels 10, 11 and 12 respectively by plungers 27, 28 and 29 respectively substantially of the same construction as the plungers 23 and actuated in substantially 30 the same manner as the same. Feelers 30, 31 and 32 co-operate with the plungers 27, 35 28 and 29 and prevent the same from operating until a group of five sets of superposed boxes has been placed in front of the plungers respectively.

As seen from above, the boxes are placed 35 on the table 13 in three rows, delivered by the channels 10, 11 and 12 respectively. Each row comprises five sub-rows located laterally of each other and each composed of sets of five superposed boxes. The channels 40 10, 11 and 12 terminate at different points *b*, *c* and *d* respectively. At each delivery point a pile *f* of paper sheets is located on the table and owing to the manner in which the boxes are delivered, a single operator 45 will be able to wrap up all the boxes into packets each comprising, for instance, fifty boxes. The boxes delivered by the machine 1 for instance must not necessarily be of the same size as those delivered by the machine 50 2 or 3 and the cigarettes may differ in quality.

Owing to the fact that the channel 7 has a considerable length, the bottom of the last part of the said channel consists of an end- 55 less belt 33, passing round rolls 34 and 35. Roll 34 is rotated by means of a ratchet wheel 36, connected with the said roll, and a pawl 37, provided on a swingable arm 38 and by means of a link 39 actuated by the 60 lever arm 20 every time the plunger 22 transmits a set of boxes from the channel 4 into the channel 7 and forwards the set of boxes located in the first part of the channel, so that the belt 33 forwards the sets of boxes 65 located in the last part of the channel simul-

taneously. A similar belt driven in the same manner forms the bottom of the last part of the channel 8.

As the boxes are delivered by the machines into the channels 4, 5 and 6 respectively, the flaps of the boxes at one end of the same generally just have been pasted together. While the boxes are moved forward in the said channels, in which they must fit rather snugly, paste not yet dried on the outside of the boxes would stick to one of the side walls of the channels and be spread on the same during the movement of the boxes, so that finally boxes can not pass through the channels. In order to remove the said disadvantage one 40 of the side walls of the channels 4, 5 and 6 is movable toward and from the opposite side wall 41 and preferably carried by two or more swingable arms 42. The side wall 40 is oscillated by any suitable motion transmitting device actuated by the driving shaft of the machine. The said wall 40 is moved from the wall 41 each time the row of boxes contained in the channels 4, 5 and 6 respectively is fed forward in the channel, thus releasing the boxes. After the feeding operation the wall 40 is again forced against the boxes.

In this manner the end flaps of the boxes are repeatedly forced against one another, 95 their sticking together being thereby ensured. Besides a sufficiently great play is provided for the boxes during each feeding operation, which results in substantially no paste being spread on the side of the channel. 100

The transporting device may evidently be modified in some respect without exceeding the limits of the invention.

We claim:

1. In a device for packeting packets delivered from a machine, the combination of a packeting table, guiding means for packets, located between the machine and the said table and comprising channels forming an angle with each other, and means for transmitting substantially horizontal sets of packets from one channel to the subsequent channel, the channel last mentioned being helicoidal for an angle of 90°, so that the said sets will be shifted to a vertical position. 105

2. In a device for packeting packets delivered from a machine, the combination of a packeting table, guiding means for packets, located between the machine and the said table and comprising channels forming an angle with each other, a plunger transmitting substantially horizontal sets of packets from one channel to the subsequent channel, the channel last mentioned being for a part 110 of its length helicoidal for an angle of 90°, so that the said sets will be shifted to a vertical position, a conveyor belt forming part of the bottom of said helicoidal channel and constituting support for the packets, and 115

120 125 130

means for driving the belt intermittently in accordance with the motion of said plunger.

3. In a device for packeting packets delivered from a machine, the combination of a 5 packeting table, guiding means for packets, located between the machine and the said table and comprising channels forming an angle with each other, means for transmitting substantially horizontal sets of packets 10 from one channel to the subsequent channel, the channel last mentioned being helicoidal for an angle of 90°, so that said sets will be shifted to a vertical position, and means for transmitting sets of packets from 15 the said helicoidal channel to another of the first mentioned channels whereby the packets are delivered on the table in rows comprising sub-rows of superposed packets.
4. In a device for packeting packets delivered by machines, the combination of a 20 packeting table common to a plurality of

machines, guiding means for packets, located between the machines respectively and the said table and each comprising channels forming an angle with each other, and 25 means for transmitting substantially horizontal sets of packets from one channel to the subsequent channel, the channel last mentioned being helicoidal for an angle of 90°, so that the said sets will be shifted to 30 a vertical position, and the said guiding means ending at different points of said table.

In testimony whereof we have affixed our signatures in presence of two witnesses. 35
